MEANS FOR AUTOMATICALLY ADJUSTING
THE STROKE OF LOCOMOTIVE PISTON
VALVES

James F. McQuilkin, Laramie, Wyo.

Application March 1, 1948, Serial No. 12,371

12 Claims. (Cl. 121—165)

1

This invention relates to a valve gear mechanism for operating the cylinder slide valves of locomotives and has for its principal object the provision of a simple, positive and highly efficient device for operating the slide valves of a locomotive, which will eliminate the multitude of levers, links and cranks, at present employed for this purpose and which will provide complete and positive control of the valves at all times.

Another object of this invention is to provide automatic means for controlling the setting of the valves in consequence of variations in back pressure in the cylinders so that the most efficient setting will be automatically obtained at all times.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side elevation of the improved valve operating mechanism illustrating its relation to the adjacent parts of a typical locomotive;

Fig. 2 is a plan view of the improved valve operating mechanism in which the adjacent portions of a locomotive are outlined diagrammatically;

Fig. 3 is an enlarged side view of an operating crank and its associated mechanism which is employed in the present invention;

Fig. 4 is a longitudinal section through the crank mechanism taken on the line 4—4, Fig. 3;

Fig. 5 is a fragmentary cross section taken on the line 5—5, Fig. 4;

Fig. 6 is an enlarged detail view of a pair of valve operating levers employed in the invention, the view being taken on the line 6—6, Fig. 2;

Fig. 7 illustrates three diagrams showing typical operating positions of the levers of Fig. 6 and

Fig. 8 is a cross section taken on the line 8—8, Fig. 4.

In the drawings, typical elements of a locomotive are diagrammatically outlined and designated by reference numerals as follows: Power cylinder 10; driving cross head 11; pilot wheels 12; drive wheels 13; drive wheel axles 14; valve boxes 15; slide valve rods 16; valve cross head guides 17; valve cross heads 18; and longitudinal frame members 19.

In applying the improved valve operated mechanism to the locomotive a double shaft consisting of an outer shaft sleeve 20 and an inner solid

2

shaft 21 is journaled in suitable journal boxes 22 across the frame members 19 so as to project from both sides thereof. The shaft sleeve 20 is driven in any suitable manner so as to rotate in the same direction and at the same speed as the axle 14.

One method of driving the sleeve 20 is illustrated in Figs. 1 and 2 and comprises a bevel drive gear 23 fixed on the axle 14 and a bevel driven gear 24, mounted on the shaft sleeve 20. A telescoping shaft 25 extends between two bevel gears 26, one meshing with the gear 23 and one with the gear 24. The shaft 25 is supported in two yokes 27 one mounted on the axle 14 and one on the shaft sleeve 20.

A crank drum 28 is fixedly mounted on each extremity of the solid shaft 21. The crank drums are cylindrical and provided with open outer faces. Two parallel slide rods 29 extend diametrically across each drum 28 in parallel relation. The drums 28 are similar. In each a crank block 30 is slidably mounted on the rods 29 so that it may move therealong. A counterweight 31 is similarly slidably mounted upon the rods 29. The crank block 30 and the counterweight 31 are caused to move towards and away from each other in unison by means of a right and left hand threaded jack shaft 32 which is threaded through the block 30 and the counterweight 31.

30 A main crank pin 33 projects from the crank block 30 and a crank arm 34 extends from the crank pin 33 to a second crank pin 35. The crank arm 34 is rigidly formed or mounted on the main crank pin 33 and extends in parallel relation with the jack shaft 32.

35 A main connecting rod 36 extends from the main crank pin 33 and a second connecting rod 37 extends from the second crank pin 35. The main connecting rod 36 is connected to the upper extremity of a floating lever 38, and the second connecting rod 37 is connected to the upper extremity of a rocking lever 39. The floating lever 38 is pivoted adjacent its upper extremity in the valve cross head 18, as is usual in locomotive construction. The rocking lever 39 is mounted intermediate its extremities on a pivot bolt 40 projecting from the valve cross head guide 17. The lower extremities of the two levers 38 and 39 are hingedly connected together by means of a connecting bolt or pin 41 which enters a vertically elongated slot 42 in the lever 39.

45 The jack screw 32 of each crank drum 28 is provided with a toothed gear 43 at each of its extremities. The gears 43 simultaneously mesh with teeth formed on the inner edges of two ring gears 44 and 45 which are rotatably mounted on the circumference of the drum 28 and held in place in any desired manner, such as by means of a flange ring 46.

50 A friction band 47 surrounds the ring gear 44.

and a similar friction band 48 surrounds the ring gear 45. The friction band 47 may be contracted to grip the ring gear 44 by means of a plunger 49, terminating in a piston 50 in a pressure cylinder 51. A spring 52 acts against the piston 50 to constantly urge the friction band 47 into engagement with the ring gear 44. It can be forced out of engagement by admitting fluid under pressure to the pressure cylinder 51 above the piston 50.

The friction band 48 may be forced into engagement with the ring gear 45 by means of a second plunger 53, terminating in a piston 54 within a second pressure cylinder 55. A spring 56 which acts against the piston 54 to constantly urge the band 48 out of engagement with the ring gear 45 and it may be contracted to the closed position by admitting fluid under pressure below the piston 54 to force it against the action of the spring 56.

The pressure cylinders 51 and 55 are connected by means of back pressure pipes 57 with the exhausts from the valve chambers 15. The usual locomotive has a back pressure pipe leading from the valve chambers to a back pressure guage in the cab. The pipes 57 may be connected directly to this if desired.

The outer shaft sleeve 20 terminates at each of its extremities in a quadrant lug a key 58 having a width of 90° and each crank drum 28 is provided with a similar projecting quadrant lug or key 59 also having a width of 90°. The keys are positioned to be contacted by the keys 58 to cause the drums 28 to rotate with the shaft sleeve 20. Since both drums are fixedly mounted on the shaft 21 they will rotate in unison.

Operation

Let us assume that the locomotive is moving forwardly. The crank drums 28 are also rotating forwardly with the drive wheels 13 and at the same speed as the latter. The crank pins 33 at the opposite sides of the locomotive are set 90° apart, similarly to the setting of the engine drivers and cross heads 11.

Each forward motion of each crank pin 33 forces the upper extremity of the floating lever 38 forwardly. The lower extremity of the lever 38 acts against the pin 41 as a fulcrum, as shown at C in Fig. 7, to force the valve rod 16 forwardly.

Each rearward movement of each crank pin 33 pulls the upper extremity of the lever 38 rearwardly, pressing against the pin 41 as shown at A in Fig. 7, to move the valve rod 16 rearwardly.

The second pin 35 provides automatic lap and lead for the slide valve. It can be seen that whenever the lever 38 swings forwardly, as at C, Fig. 7, the pin 35 will be moving rearwardly. This rearward movement is communicated to the upper extremity of the lever 39, causing it to pivot about the bolt 40 so as to swing the fulcrum pin 41 forwardly to increase the forward motion of the valve. The same action takes place when the pin 35 swings rearwardly to increase the rearward movement of the valve.

The length of the stroke of the valve can be varied by moving the main crank pin 33 toward or away from the axis of the shaft 21. This can, of course, be accomplished by rotating the jack screw 32 in one direction or the other. This adjustment must be made while the drums 28 are in motion, and is accomplished through the medium of the ring gears 44 and 45 and their friction bands 47 and 48.

For instance, if in Fig. 4 the band 47 is brought into contact with the ring gear 44, it will tend to resist rotation of the latter, causing the gears 43 to travel along the teeth of the gear 44 and impart rotation to the jack shaft 32 causing it to thread itself into both the crank block 30 and the counterweight 31, so as to move them toward the axis of the shaft 21.

If the band 47 is released and the band 48 tightened, the gears 43 will travel in the other direction along the teeth of the retarded ring gear 45, rotating the shaft 32 in the other direction to separate the crank block 30 and the counter-weight 31. Thus, any desired degree of eccentricity for the crank pin 33 can be obtained by manipulation of the frictional engagement of the bands 47 and 48.

This manipulation is automatically accomplished from the pressure in the black pressure pipe 57. Should the black pressure in the cylinders increase, it will flow into the pressure cylinders 55, clamping the friction bands 48, and will flow into the pressure cylinders 51, releasing the friction bands 47, causing the jack shaft to shorten the crank stroke and shorten the valve stroke. Should the back pressure fall below a minimum determined by the springs 52, the latter springs will apply the band 47 and the spring 55 will release the band 48 to bring the back pressure to the desired minimum.

It will be noted that the stroke of the second crank pin 35 increases as the stroke of the main crank pin 33 decreases. Therefore, the lap and lead of the valve will be controlled in inverse ratio to the stroke thereof, which, of course, is the desirable condition.

In order to reverse the locomotive, it is necessary that the crank pins 33 and 35 be rotated 180°. This may be accomplished in any desired manner. One method of accomplishing it is to provide gear teeth 60 on the drums 28 with which toothed rack bars 61 may be brought into engagement. The rack bars 61 extend to any desired operating mechanism in the cab of the locomotive, by means of which they may be lowered into engagement with the teeth 60 and forced forwardly sufficiently to rotate the drums 28 and their connecting shaft 21 forwardly 180°. The racks are then lifted from engagement with the teeth 60.

The drums are free to rotate forwardly, since the keys 58 thereon simply move away from the keys 59 on the shaft sleeve 20 to the broken line position in Fig. 5. This places the keys 58 on the opposite side of the keys 59 so that as the latter move in the reverse direction, they will again contact the keys 58 and rotate the drums in the reverse direction.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A valve gear for operating the slide valve rods of a locomotive having a drive wheel axle comprising: a shaft extending transversally of said locomotive; means for driving said shaft from said axle; a first eccentric crank pin at each extremity of said shaft; means for varying the distance between the axis of said crank pins and the axis of said shaft; a crank arm fixed

to and extending from each of said crank pins diametrically across the axis of said shaft; a second crank pin mounted on the extremity of each of said crank arms; a first connecting rod extending from each of the first eccentric crank pins; a second connecting rod extending from each of the second crank pins; a floating lever pivoted intermediate its extremities on each of said valve rods, said first connecting rods connecting with the upper extremities of said floating levers; a swinging lever pivoted adjacent to each of said floating levers; said second connecting rods being connected to the upper extremities of said swinging levers; and means hingedly connecting the lower extremities of said floating levers to said swinging levers.

2. A valve gear for operating the slide valve rods of a locomotive having a drive wheel axle comprising: a shaft extending transversally of said locomotive; means for driving said shaft from said axle; a crank drum at each extremity of said shaft; a first crank pin supported from each drum; a crank arm fixed to and extending from each of said crank pins diametrically across the axis of said shaft; a second crank pin mounted on the extremity of each of said crank arms; a first connecting rod extending from each of the first crank pins; a second connecting rod extending from each of the second crank pins; a floating lever pivoted intermediate its extremities on each of said valve rods, said first connecting rods connecting with the upper extremities of said floating levers; a swinging lever pivoted adjacent to each of said floating levers, said second connecting rods being connected to the upper extremities of said swinging levers; means hingedly connecting the lower extremities of said floating levers to said swinging levers; and means for simultaneously moving both crank pins diametrically of each drum to vary the stroke of said pins.

3. A valve gear for operating the slide valve rods of a locomotive having a drive wheel axle comprising: a rotatable shaft journalled on said locomotive and extending parallel to said axle; a crank drum secured on each extremity of said shaft; a crank block slidably mounted in each crank drum so as to move diametrically thereof; a crank pin projecting from each crank block; means connecting each crank pin with one of the valve rods of said locomotive; and means for rotating said shaft from said axle.

4. A valve gear for operating the slide valve rod of a locomotive having a drive wheel axle comprising: a rotatable shaft journalled on said locomotive and extending parallel to said axle; a crank drum secured on the extremity of said shaft; a crank block slidably mounted in said crank drum so as to move diametrically thereof; a crank pin projecting from said crank block; a jack screw extending across said drum and being threaded through said crank block; means for rotating said jack screw to vary the eccentric position of said block; means connecting said crank pin with the valve rod of the locomotive; and means for rotating said shaft from said axle.

5. A valve gear for operating the slide valve rods of a locomotive having a drive wheel axle comprising: a rotatable shaft journalled on said locomotive and extending parallel to said axle; a crank drum secured on each extremity of said shaft; a crank block slidably mounted in each crank drum so as to move diametrically thereof; a crank pin projecting from each crank block;

a jack screw extending across each drum and being threaded through the crank block therein; a driven gear on the extremity of each of said jack screws; two ring gears surrounding each crank drum in mesh with the opposite sides of the driven gear therein; means for retarding rotation of either of the two ring gears on a drum so as to impart rotation to said driven gear to cause the jack screw of that drum to vary the position of the crank pin therein; means extending from each crank pin to a connection with a valve rod of the locomotive; and means for driving said shaft from said axle.

6. A valve gear for operating the slide valve rods of a locomotive having a drive wheel axle comprising: a rotatable shaft journalled on said locomotive and extending parallel to said axle; a crank drum secured on each extremity of said shaft; a crank block slidably mounted in each crank drum so as to move diametrically thereof; a crank pin projecting from each crank block; a jack screw extending across each drum and being threaded through the crank block therein; a driven gear on the extremity of each of said jack screws; two ring gears surrounding each crank drum in mesh with the opposite sides of the driven gear therein; an independent friction device for each ring gear positioned to contact the latter; a pressure responsive device mounted to bring one of said friction devices into contact with one of said ring gears; a second pressure responsive device arranged to force the second friction device out of contact with the second ring gear; spring means for moving said friction devices opposite to the movement of said pressure responsive devices; a conduit connecting said pressure responsive devices with the exhaust of said locomotive; means connecting each crank pin with a valve rod of said locomotive; and means for rotating said shaft from said axle.

7. Means for reciprocating the valve cross head of a locomotive comprising: a floating lever passing through said cross head and extending above and below the latter; a swinging lever pivoted alongside said floating lever and extending above and below the pivot thereof; hinge means connecting the lower extremity of said swinging lever to the lower extremity of said floating lever; an actuating shaft; a first eccentric crank pin carried by said shaft to one side of its axis; a second eccentric crank pin carried by said shaft to the opposite side of its axis; a first connecting rod extending rearwardly from the upper extremity of said floating lever to said first crank pin; a second connecting rod extending rearwardly from the upper extremity of each swinging lever to said second crank pin so that said connecting rods will be moved in opposite directions due to the opposite eccentricity of said crank pins; and means for rotating said actuating shaft in consequence of the movement of said locomotive.

8. Means for reciprocating the valve cross heads of a locomotive comprising: a floating lever passing through each cross head and extending above and below the latter; a swinging lever pivoted alongside each floating lever and extending above and below its pivot; hinge means connecting the lower extremity of said swinging lever to the lower extremity of said floating lever; a first connecting rod extending rearwardly from the upper extremity of each floating lever; a second connecting rod extending rearwardly from the upper extremity of each swinging lever; a valve shaft extending across said locomotive

rearwardly of said connecting rods; a crank drum on each extremity of said shaft; a crank block positioned to move diametrically of each crank drum; a first crank pin extending outwardly from each of said crank blocks upon which the rear extremities of the first connecting rods are mounted; a crank arm fixed to and extending diametrically from each of said crank pins to a position on the opposite side of the axis of said shaft; a second crank pin mounted on the extremity of each crank arm upon which the rear extremities of said second connecting rods are mounted; and means for rotating said shaft in consequence of the movement of said locomotive.

9. Means for reciprocating the valve cross heads of a locomotive comprising: a floating lever passing through each cross head and extending above and below the latter; a swinging lever pivoted alongside each floating lever and extending above and below its pivot; hinge means connecting the lower extremity of said swinging lever to the lower extremity of said floating lever; a first connecting rod extending rearwardly from the upper extremity of each floating lever; a second connecting rod extending rearwardly from the upper extremity of each swinging lever; a valve shaft extending across said locomotive rearwardly of said connecting rods; a crank drum on each extremity of said shaft; a crank block positioned to move diametrically of each crank drum; a first crank pin extending outwardly from each of said crank blocks upon which the rear extremities of the first connecting rods are mounted; a crank arm fixed to and extending diametrically from each of said crank pins to a position on the opposite side of the axis of said shaft; a second crank pin mounted on the extremity of each crank arm upon which the rear extremities of said second connecting rods are mounted; means for rotating said shaft in consequence of the movement of said locomotive; a diametrically extending jack screw rotatably mounted in each crank drum and being threaded through the crank blocks therein; and means for rotating said jack screws while said crank drums are rotating for varying the radial positions of said crank pins.

10. Means for reciprocating the valve cross heads of a locomotive comprising: a floating lever passing through each cross head and extending above and below the latter; a swinging lever pivoted alongside each floating lever and extending above and below its pivot; hinge means connecting the lower extremity of said swinging lever to the lower extremity of said floating lever; a first connecting rod extending rearwardly from the upper extremity of each floating lever; a second connecting rod extending rearwardly from the upper extremity of each swinging lever; a valve shaft extending across said locomotive rearwardly of said connecting rods; a crank drum on each extremity of said shaft; a crank block positioned to move diametrically of each crank drum; a first crank pin extending outwardly from each of said crank blocks upon which the rear extremities of the first connecting rods are mounted; a crank arm fixed to and extending diametrically from each of said crank pins to a position on the opposite side of the axis of said shaft; a second crank pin mounted on the extremity of each crank arm upon which the rear extremities of said second connecting rods are mounted; means for rotating said shaft in con-

sequence of the movement of said locomotive; a diametrically extending jack screw rotatably mounted in each crank drum and being threaded through the crank blocks therein; means for rotating said jack screws while said crank drums are rotating for varying the radial positions of said crank pins; said latter means for rotating being operable by and in consequence of variations of the pressure of the exhaust steam of said locomotive.

11. Means for reciprocating the valve cross heads of a locomotive comprising: a floating lever passing through each cross head and extending above and below the latter; a swinging lever pivoted intermediate its extremities alongside each floating lever; hinge means connecting the lower extremity of said swinging lever to the lower extremity of said floating lever; a first connecting rod extending rearwardly from the upper extremity of each floating lever; a second connecting rod extending rearwardly from the upper extremity of each swinging lever; a valve shaft extending across and terminating at each side of said locomotive rearwardly of said connecting rods; a pair of fixedly-spaced, eccentrically-positioned crank pins carried at each extremity of said shaft, the pins of each pair being positioned on opposite sides of the axis of said shaft, the first and second connecting rods at each side of said locomotive being respectively connected to the two pins of the pair of pins at that side; and means for rotating said shaft in consequence of the movement of said locomotive.

12. Means for reciprocating the valve cross heads of a locomotive comprising: a floating lever passing through each cross head and extending above and below the latter; a swinging lever pivoted intermediate its extremities alongside each floating lever; hinge means connecting the lower extremity of said swinging lever to the lower extremity of said floating lever; a first connecting rod extending rearwardly from the upper extremity of each floating lever; a second connecting rod extending rearwardly from the upper extremity of each swinging lever; a valve shaft extending across and terminating at each side of said locomotive rearwardly of said connecting rods; a pair of fixedly-spaced, eccentrically-positioned crank pins carried at each extremity of said shaft, the pins of each pair being positioned on opposite sides of the axis of said shaft, the first and second connecting rods at each side of said locomotive being respectively connected to the two pins of the pair of pins at that side; means for rotating said shaft in consequence of the movement of said locomotive; and means for moving the pairs of pins diametrically of the axis of said shaft by, and in consequence of variations of, the pressure of the exhaust steam of said locomotive.
